UNITED STATES PATENT OFFICE.

JOHN LUNDIE, OF NEW YORK, N. Y.

TIE PLATE.

Application filed November 24, 1925. Serial No. 71,037.

The present invention relates to improvements in railroad tie-plates.

Among the principal objects of the invention are to provide a tie-plate which will effectively engage a railroad tie and prevent spreading of the track; to provide such a plate which will not injure the fibres of the tie upon which it is mounted; to provide such a device which will support a rail in a position normal to the coned-tread of a wheel; and to provide such a device which may readily be rolled end over end to facilitate economical manufacture.

With these and other objects in view, the invention resides in the novel features of construction, combination and arrangement of parts hereinafter set forth, illustrated in the accompanying drawings and specifically pointed out in the appended claims.

In my re-issue Letters Patent No. 4,124 of May 2, 1916, a tie-plate is disclosed wherein the rail-seat is disposed in a line normal to the resultant of the downward force on the rail and the lateral thrust. The bottom surface of said tie-plate preferably has a plurality of stepped bearing surfaces which are parallel to the rail-seat whereby to prevent outward slipping of the tie-plate on the tie. With such a structure the tie-plate becomes embedded in the surface of the tie after a few train-loads have passed over the rail which it supports and in view of the fact that there are no pronounced shoulders between the adjacent bearing surfaces, the fibres of the tie will not be injured. While the tie-plate disclosed in said re-issue patent has very effectively met all of the technical requirements, there has been some demand from railroad men for a tie-plate which in their opinion would take a more secure bite in the tie, especially into the prevailing soft wood ties of today. These ties are now being almost universally creosoted to preserve their life, thus the saving of them from destruction is a very important factor in the cost of railway maintenance. It is evident, therefore, that any device which will give great holding power to tie-plates, and, at the same time, preserve the tie from injury, is a distinct element in railway economy.

In my U. S. Letters Patent No. 1,333,860, issued March 16, 1920, I have shown another tie-plate having a plurality of inclined bearing surfaces on its lower side and further provided with substantial abrupt

shoulders between the adjacent bearing surfaces.

The structure of the present invention is a compromise between the structures of the two above mentioned patents.

Referring now to the drawings wherein similar reference characters designate corresponding parts throughout the several views:

Fig. 1 is a transverse sectional view, showing the improved tie-plate in use for supporting a rail on a tie;

Fig. 2 is a bottom plan view of the tie-plate, and

Fig. 3 is an end elevation of the same looking toward the inside edge.

The reference character 10 designates a railroad tie of the ordinary wood construction, upon which is mounted my improved tie-plate 11 for the support of a rail 12. The reference character 13 designates a railroad car-wheel having the usual coned-tread, the taper of which is at the present time standardized as 1 in 20, but which may be 1 in 40 or any other desirable ratio.

The tie-plate 11 has on its upper surface a rail-seat 14 which is inclined downwardly toward its inner edge as clearly shown in Fig. 1, the inclination being of substantially the same degree as the taper on the tread of the wheel 13. Adjacent its outer edge, the plate 11 has an upwardly extending rail abutting shoulder 15 against which the outer edge of the rail flange may be positioned.

The lower surface of the tie-plate 11 is formed with a plurality of bearing surfaces 16 which are also inclined downwardly but having a greater inclination than the rail-seat 14.

It obviously would not do to run these steps in the opposite direction, either with a greater or less inclination, as this would tend to make the plate slip outward, except for the holding power of what is equivalent to ribs at the junction of the steps, and this action would tend to destroy the tie. The adjacent bearing surfaces 16 are joined or merged by ogee curves 17 whereby to eliminate abrupt shoulders and thus to prevent injury to the fibres of the tie 10. In a direction parallel to the rail, the plate 11 is cambered as clearly shown in Fig. 3, whereby to provide a resilient seating of the plate upon the tie and any desired number of spike holes 18 may be formed in the plate for the recep-

tion of the usual fastening spikes 19 by which the plate and the rail are secured to the tie.

From the foregoing it will be evident that the resultant of the downward force on the rail and the lateral thrust will pass through the center of the web of the rail in such a manner as to distribute the said pressure evenly upon the base flanges of the rail, and by this action the wear on the rail and on the wheel will be even so as to assure long life of such equipment. The plate 11 is positioned upon the tie 10 and the rail 12 subsequently applied thereto and held in place by spikes 19, and after several train-loads have passed over the rail 12, the bearing surfaces 16 and their merging curves 17 become embedded in the upper surface of the tie 10 without injury to the fibres thereof. In view of the fact that the bearing surfaces 16 have a greater inclination than the rail-seat 14, the plate may be more securely held against outward slipping on the tie 10 than has been possible with the structure shown in my previously mentioned re-issue patent. Also it is to be noted that the inclined bearing surfaces are more numerous than in said patent. These features, besides taking a firmer bite in the tie, make it possible to roll the tie-plate stock end over end, forming the camber in the same rolling operation, thus facilitating the manufacture as will be readily apparent to those skilled in the art.

Obviously changes may be resorted to in the details of construction and the proportion of parts, and the right is herein reserved to make such changes falling within the scope of the appended claims without departing from the spirit of the invention.

I have stated herein that my improved tie-plate may be rolled end over end. By this I mean that it may be rolled in a direction transverse to the rail-abutting shoulder in contradistinction to the method of rolling my earlier tie-plates which were formed longitudinally with respect to the rail-abutting shoulder. The end over end rolling may be used in forming elongated stock from which individual plates may subsequently be sheared, and as has previously been pointed out, such rolling permits the simultaneous formation of the camber.

What I claim is:

1. A tie-plate having an upper surface inclined downwardly toward the inner edge, and forming a rail-seat, and stepped bottom surfaces which are inclined downwardly from the upper surface toward the said inner edge of the plate.

2. A tie-plate having an upper surface inclined downwardly toward the inner edge, and forming a rail-seat, and stepped bottom surfaces which are inclined downwardly from the upper surface toward the said in-

ner edge of the plate, said plate being cambered between the two remaining edges.

3. A tie-plate having a rail-seat normal to the line of thrust of a coned-tread car wheel and which is of gradually increasing thickness from its inner edge toward its outer edge, and stepped bottom surfaces having portions which are slightly inclined relatively to the rail-seat, said inclined portions extending downwardly toward the inner edge of the plate.

4. A tie-plate having a rail-seat normal to the line of thrust of a coned-tread car wheel and which is of gradually increasing thickness from its inner edge toward its outer edge, and stepped bottom surfaces having portions which are slightly inclined relatively to the rail-seat, said inclined portions extending downwardly toward the inner edge of the plate, and said plate being cambered between the two remaining edges.

5. A tie-plate having an inclined upper surface forming a rail-seat, and a bottom surface having a plurality of inclined portions of greater inclination than the rail-seat and extending in the same general direction, said inclined portions being joined by merged curves.

6. A tie-plate of the character described having under stepped projections parallel to the length of the rail, each stepped projection having a bearing surface which is inclined upwardly and outwardly toward the outer edge of the plate and with respect to the horizontal plane of the edges of said projections and which is out of parallel with the rail-bearing surface of the plate, said projections being of rounded or convex form at said edges.

7. A tie-plate of the character described having an inclined rail-bearing surface, under stepped projections parallel to the length of the rail, each stepped projection having a bearing surface which is inclined upwardly and outwardly with respect to the horizontal plane of the edges of said projections and in the general direction of upward inclination of the inclined rail-bearing surface and so that it is out of parallel with the rail-bearing surface of the plate, and the plate having inner corners between the stepped portions, which inner corners are successively located nearer to the rail-bearing surface as the inner edge of the plate is approached.

8. A tie-plate having a rail-seat normal to the line of thrust of a coned-tread car wheel and which is of increasing thickness from its inner edge toward its outer edge, and a bottom surface having a plurality of bearing surfaces of greater inclination than the rail-seat and extending in substantially the same direction as said rail seat, the adjacent bearing surfaces being joined together by merged curves, and the entire

plate being cambered in a direction parallel to the rail.

9. A cambered tie-plate having a rail-seat on its upper surface, means for resisting outward thrust of a rail, and a plurality of relatively wide stepped bearing surfaces on the lower side of the plate, said bearing surfaces being slightly inclined downwardly and inwardly away from said resisting means.

10. A tie-plate having a rail-abutting shoulder adjacent its outer edge, and provided with an upper surface inclined downwardly toward the inner edge to form a rail-seat, and stepped bottom surfaces which are inclined downwardly with reference to the upper surface and toward the said inner edge of the plate. 15

JOHN LUNDIE.
